UNITED STATES PATENT OFFICE

151,856

DESIGN FOR A VEGETABLE SLICER

Arthur William Norman, Largo, Fla., assignor to
The Hobart Manufacturing Company, Troy,
Ohio, a corporation of Ohio

Application May 7, 1947, Serial No. 138,865

Term of patent 14 years

(Cl. D89—1)

To all whom it may concern:

Be it known that I, Arthur William Norman, a citizen of the United States of America, residing at Largo, in the county of Pinellas and State of Florida, have invented a new, original, and ornamental Design for Vegetable Slicer, of which the following is a specification, reference being had to the accompanying drawings, forming a part thereof, in which

Fig. 1 is a view in side elevation of a vegetable slicer constructed in accordance with my new design;

Fig. 2 is a top plan view of the same;

Fig. 3 is a perspective view from a position above the operator's end of the machine and looking toward the feeding opening;

Fig. 4 is a perspective view from the delivery side of the device;

Figs. 5 and 6 are end elevational views from

the delivery side and the feeding side respectively; and

Fig. 7 is a perspective view from the same end of the machine as Fig. 3 but taken from a lower angle.

My design for a vegetable slicer is characterized by the configuration of the base member having an undercut forwardly projecting area in combination with the overlying cover which has a trough-like portion projecting therefrom in a direction opposite to and at a higher level than the projecting undercut area, all as shown in the drawing.

I claim:

The ornamental design for a vegetable slicer, as shown and described.

ARTHUR WILLIAM NORMAN.
